The ornamental design for a car rearview monitor, as shown and described.

DESCRIPTION

FIG. 1 is a front perspective view of a car rearview monitor showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of a portion of the bottom of the car rearview monitor.

The broken lines in the drawings depict portions of the car rearview monitor that form no part of the claimed design. The broken line showing within the U-shaped area and the two rectangular areas on either side thereof in FIG. 7 comprise tight areas of broken lines and forms no part of the claimed design.
